(57) **CLAIM**

The ornamental design for a hand-held computer case, as shown and described.

DESCRIPTION

FIG. 1 is a front perspective view of a hand-held computer case showing my new design;

FIG. 2 is a rear perspective view of the hand-held computer case of FIG. 1;

FIG. 3 is a front view of the hand-held computer case of FIG. 1;

FIG. 4 is a rear view of the hand-held computer case of FIG. 1;

FIG. 5 is a left side view of the hand-held computer case of FIG. 1;

FIG. 6 is a right side view of the hand-held computer case of FIG. 1;

FIG. 7 is a top view of the hand-held computer case of FIG. 1; and,

FIG. 8 is a bottom view of the hand-held computer case of FIG. 1.
